UNITED STATES PATENT OFFICE.

HENRY KEELER, OF EUREKA, ILLINOIS.

COMBINED IRONING-TABLE AND CLOTHES-BARS.

SPECIFICATION forming part of Letters Patent No. 252,675, dated January 24, 1882.

Application filed April 20, 1881. (No model.)

To all whom it may concern:

Be it known that I, HENRY KEELER, of Eureka, in the county of Woodford, in the State of Illinois, have invented an Improved Combined Ironing-Table and Clothes-Bars; and I do hereby declare that the following is a full, clear, and exact description thereof, reference being had to the annexed drawings, making a part of this specification, in which like letters of reference refer to like parts, and in which—

Figure 1 represents a sectional elevation through the center of board B at αx ; Fig. 2, a view of table folded up; Fig. 3, a perspective view.

The pair of legs C C are pivoted at E to the other pair of legs, A A, and also by means of the set-offs F F to the under side of the board B. The other extremity of the board B is supported by the cross-bar G, being retained at different heights by the ratchet-bar R, bolted to said board B. The legs A A have their upper ends prolonged and furnished with cross-bars H' H' H². By means of the short pieces D' D' and the cross-bars H and H² the strips D D are attached to the upper ends of said prolonged legs A A; and for the further reception of clothes, cross-bars H' extend between and beyond said strips D D.

To fold up this ironing-table and clothes-bars, the upper ends of legs A A and C C are pressed toward each other, the ratchet R and

top B sliding over the cross-bar G until the offset F comes against said bar G, when the ratchet end of said board B falls down till it is flat against the lower ends of the legs. The strips D D being folded down against the ironing-board B, the whole is brought snugly together in its most compact form.

The table is adjusted to different heights by catching the cross-bar G at points in the ratchet R nearer or farther away from the set-offs F F.

The free ends of the strips D D can rest either upon the floor, high up against the wall, over upon the back part of the stove, or wherever most convenient.

What I claim as my invention, and for which I desire Letters Patent, is as follows, to wit:

The ironing-board B, having set-offs F F and ratchet R, in combination with the legs C C, cross-bar E, extended legs A A, having cross-bars, G, H', H', and H², short strips D' D', and strips D D, having cross-bars H H', substantially as and for the purpose specified.

In testimony that I claim the foregoing invention I have hereunto set my hand this 13th day of April, 1881.

HENRY KEELER.
